UNITED STATES PATENT OFFICE.

CHARLES H. FRYE, OF SALT LAKE CITY, UTAH.

HEADLIGHT-BLIND.

1,142,414.

Specification of Letters Patent.

Patented June 8, 1915.

Application filed September 28, 1914. Serial No. 863,945.

To all whom it may concern:

Be it known that I, CHARLES H. FRYE, a citizen of the United States, residing at Salt Lake City, in the county of Salt Lake and State of Utah, have invented certain new and useful Improvements in Headlight-Blinds, of which the following is a specification, reference being had to the accompanying drawings.

10 This invention comprehends certain new and useful improvements in locomotive headlight blinds that are designed to be thrown over the headlight of a locomotive when the same is standing on a siding for 15 the purpose of screening the light whereby the crew of the train approaching from the opposite direction on the main line will see the headlight of the locomotive upon the siding, and all liability of confusion will be 20 thereby avoided.

As is well known, it has been customary in devices of this character, to operate the blind by hand, by the fireman, for example, walking out on the running board of the locomotive and pulling the blind down manually, and while it has been proposed to operate devices of this kind by air under the control of the engineer in the locomotive cab and thus obviate the dangers and 30 inconveniences of the operation just mentioned, yet the primary object of my invention is a more simple and efficient arrangement and construction of the parts of an air controlled headlight blind than have heretofore been employed.

It is also well known to those familiar with the art to which this invention appertains, that these blinds ordinarily do not display the number of the locomotive to 40 which they are attached, and it is to be understood that in the present instance, my improved blind is thus provided with the number of the engine, whereby the identity of the train passing on the main line may be at once shown to the crew on the siding so that they may know that the superior train has passed, this device being also useful in that when an inferior train on a piece of 45 double track road is given the right over the superior train to the station at the end of the double track, and the inferior train gets there first, and the two trains pass on the double track, the engineers of both 50 trains may cover their headlights while 55 passing each other so as to allow the crew

of each train to positively read the numbers on the headlights of the other engine, thereby eliminating the stopping and checking of the register which involves a delay of from five to eight minutes at a double 60 track station.

The construction and arrangement of the parts whereby these advantageous results may be obtained, will be hereinafter fully described and are illustrated in the accompanying drawing, in which,

Figure 1 is a side elevation of my device, parts being shown in section. Fig. 2 is a front view thereof. Fig. 3 is an enlarged end view of the curtain protecting hood and 70 the spring actuated roller mounted therein.

Corresponding and like parts are referred to in the following description and designated in all of the views of the accompanying drawing by like reference characters.

Referring to the drawing, the numeral 1 designates the headlight of a locomotive, and 2 designates preferably a metal hood of curved formation in cross section, said hood being extended laterally on and in 80 front of the headlight and secured to the top thereof and at the front by rivets or any other suitable fastening devices. The hood 2 is open at the bottom, as best illustrated in Fig. 3. Journaled within the hood 85 2 is a roller 3 which is held under tension by coil springs 4, as shown, and on which is mounted the flexible shade 5 of cloth or other suitable substance or material, the shade being normally held wound upon the 90 roller and the hood 2 protecting the parts from the elements.

Secured to the lower edge of the shade 5 is a cord or other flexible connecting member 6, the lower end of which is fastened to 95 the forward end of a lever 7 which is pivotally mounted underneath the headlight support, as at 8; and which is connected intermediate of its ends by the slot and pin connection 9 with the lower end of a vertically 100 disposed rod 10 which passes up through a stuffing box 11 secured to the lower end of a vertically disposed cylinder 12 secured to the headlight support underneath the latter. The rod 10 is provided at its upper end 105 within the cylinder 12, with a piston head 13 and it is encircled within the cylinder with an expansion spring 14 which bears against the lower side of the head 13 and reacts against the stuffing box 11 so as to exert a 110

tension on the head and tend to move the rod 10 and lever 7 upwardly so as to allow the springs 4 to act to turn the roller 3 and wind up the curtain 5. The cylinder 12 is formed with a port 15 above the piston head 13 and leading to the port is a pipe 16 for air, said pipe extending rearwardly and being connected to some suitable source of air supply (not shown) controlled by the engineer in the locomotive cab.

From the foregoing description in connection with the accompanying drawing, the operation of my improved headlight will be apparent. Normally, the blind will be wound upon the roller 3 and entirely housed and contained within the downwardly opening hood 2. When it is desired to shield the light and show the number of the locomotive which is displayed on the blind 5, it is only necessary for the engineer to admit air into the pipe 16, whence it will pass to the cylinder 12 and force the piston downwardly and draw the curtain or shade 5 down over the front of the headlight, thereby screening the light and at the same time displaying the number of the locomotive. Just as soon as the screening of the light is no longer desired, it is only necessary for the engineer to allow the air to escape from the cylinder 12 and pipe 16, whereupon the spring 14 will act to move the piston and lever 7 upwardly and thus the springs 4 will be permitted to exert their tension upon the roller 3 to wind up the screen or shade.

While the accompanying drawing illustrates what I believe to be the preferred embodiment of my invention, it is to be understood that the invention is not limited thereto, but that various changes may be made in the details of construction, proportions and arrangements of the parts without

departing from the scope of the invention as defined in the appended claims.

It is to be further noted that as engines are seldom assigned to regular trains, the importance of my invention can be readily appreciated, for whatever train the engine is pulling, the number of the locomotive will be distinctly seen on the blind, either by day or night, if the blind is pulled down. 50

What is claimed, is:

1. A headlight blind for locomotives including a movable shade mounted upon the upper end of the headlight casing, a lever fulcrumed at its rear end below the headlight, a flexible element connecting the forward end of said lever to one end of the shade, and fluid actuated means also mounted below the headlight and directly connected to the lever intermediate of its ends to actuate the same and pull the shade downwardly over the headlight lens. 55

2. A headlight blind for locomotives including a movable shade mounted upon the headlight and vertically movable with respect thereto, a lever fulcrumed at its rear end below the headlight, a flexible element connecting the forward end of said lever to the lower edge of the shade, a cylinder mounted beneath the headlight, and a fluid actuated spring held piston arranged in said cylinder and connected to said lever intermediate of its ends to actuate the latter whereby the shade is pulled downwardly over the headlight lens. 75

In testimony whereof I hereunto affix my signature in the presence of two witnesses.

CHARLES H. FRYE.
